United States Patent Office.

H. NELSON CHAPMAN, OF WASHINGTON, DISTRICT OF COLUMBIA.

Letters Patent No. 87,757, dated March 16, 1869.

IMPROVED CURTAIN-FIXTURE.

The Schedule referred to in these Letters Patent and making part of the same.

To all whom it may concern:

Be it known that I, H. NELSON CHAPMAN, of Washington city, in the county of Washington, and District of Columbia, have invented certain new and useful Improvements in Curtain-Fixtures; and I do hereby declare that the following is a full, clear, and exact description of the same, reference being had to the accompanying drawing, and to the letters of reference marked thereon, making part of this specification, in which—

Figure 1 is a side view of the bracket, with clamp-plate, cord, and pulley attached.

Figure 2 is a front view of the same.

Figure 3 is a side view of the bracket, in which the same is constructed of an ordinary wire rod.

Figure 4 is a front view of a shoulder at the head of the screw, to prevent the bracket being inserted in too far into the window-casing.

The nature of my invention consists in constructing the bracket, which retains and holds the cord that elevates the window-curtain, of a simple circular rod, the same being made of iron, brass, or any other suitable metal, and can be either cast or wrought.

The base of the bracket may be a flat or triangular surface, as shown in figs. 1 and 2, or a simple rod, as shown in fig. 3.

In either case, it is provided with a gimlet-pointed screw, by means of which it can readily be attached to the window-frame or casement at any desired point.

It will readily be seen, by reference to figs. 1 and 2, that when the bracket is constructed in the form therein shown, *i. e.*, with a base-plate, that it is susceptible of the highest degree of ornamentation.

My entire bracket consists simply of three features, the bracket-rod, clamp-plate, and pulley, or swivel. Its construction is of the simplest form possible. It is impossible for any feature to become disarranged so as to interfere with its successful operation. It can be made either plain or in the most chaste and artistic style, and in either case at a most trifling expense. It can readily be attached at any point desired, and still, owing to the circular rod, and arrangement of clamp-plate thereon, its angle of bearing can be so adjusted that the cords will never cross, but always work parallel to each other. This is a most important feature, as it prevents the cords from wearing and fraying out, as is the case with the brackets now in use.

To enable others skilled in the art to make and use my invention, I will now proceed to describe its construction and operation.

A is the bracket, which may be made of iron, brass, or any other suitable metal, and either cast, wrought, or "struck up."

It may be of any desired form, care alone being taken that its main stem *a* shall be circular and of the same diameter throughout.

It may be constructed of ordinary wire, having its base swan-neck in form, or deep S-shaped, as shown

in fig. 3, or its main stem or shaft may be made in the form of a column, representing in design either of the well-known forms or styles met with in architecture, except the gradual tapering as you approach the top, which must be avoided.

The column, if desired, may be surmounted by a small globe or other device, as shown in the drawing.

It may also be provided with a base-plate, B, on which can be represented any scene, figure, or symbol that may be desired.

It will be seen that the bracket can be made not only beautiful in form, but also enriched with the most chaste and elaborate design, and at a most trifling expense.

The bracket is provided with a gimlet-pointed screw, C, by means of which it can be readily attached to any window or casement.

On the bracket, and immediately at the head of the screw-thread, there is a shoulder, c.

This shoulder may be either circular, square, triangular, or heart-shaped in form.

It prevents the screw from being inserted too far into the frame or casement, and at the same time, after the bracket has been attached, it furnishes a bearing for the same, and prevents all tendency to yield, or give, in an upward direction, when the strain of the cord is brought to bear on the bracket.

D is a clamp-plate, and is made of metal, and in any desired form.

It is provided with a circular opening, or eye, d.

The diameter of this opening, or eye *d*, is a little greater than is the diameter of the stem *a* of the bracket A, which allows of its being moved freely along the entire surface of the same.

This clamp-plate D is also provided with a short pin or arm, e, on which is firmly secured, but so secured as to allow of its unobstructed revolution, by means of a welded head or equivalent device, e', a grooved or furrowed pulley, E.

In the groove on this pulley works the curtain-cord F.

It will be observed that my clamp-plate consists of one piece, and of one piece only, of flat metal.

All joints, pivots, hinges, and lugs, being unnecessary to its operation, are dispensed with in its construction.

The bracket A being secured, by means of the screw C, to the window-frame or casement, the cord F is passed over the pulley E. The clamp-plate D is then brought on a line at right angles to the stem *a*, and moved down the same until the cord F is taut. The pressure then being removed from the clamp-plate D, the pressure of the cord will draw the clamp-plate out of its right-angle bearing, and the clamp-plate and pulley will be firmly held simply by the friction-bearing of the eye of the plate on the stem at the desired point, and the greater the strain, the more secure the bearing.

It will be observed that, owing to the circular forma-

tion of the stem *a*, no matter what the angle of bearing may be in relation to the upper pulley on the curtain-rod, the clamp-plate can be so adjusted that the cords shall always work perfectly parallel, thus avoiding all crossing, and the consequent wearing and fraying of the same, which wearing and fraying is great, and soon wears out the cord, especially when used in elevating large and heavy curtains.

My improvement has been thoroughly tested, and experience has abundantly proven its practical utility and complete success.

Having thus fully described my invention,

What I claim therein as new, and desire to secure by Letters Patent of the United States, is—

The bracket *A*, having a circular stem, *a*, clamp-plate, *D*, and pulley, *E*, when the same are so combined and arranged as to operate substantially as described, as and for the purpose specified.

In testimony whereof, I have signed my name to this specification, in the presence of two subscribing witnesses.

Witnesses: **H. NELSON CHAPMAN.**
EDWIN JAMES,
H. G. HOLMEAD.
